CLAIM

The ornamental design for a bracelet, as shown and described.

DESCRIPTION

FIG. 1 is a perspective view of a bracelet showing our new design;

FIG. 2 is a top view of the bracelet of FIG. 1;

FIG. 3 is a bottom view of the bracelet of FIG. 1;

FIG. 4 is a right side view of the bracelet of FIG. 1, the left side view being a mirror image thereof; and,

FIG. 5 is a right side view of the bracelet of FIG. 1 with opposite ends of the bracelet being connected by the clasp. The broken lines in the Figures show portions of the bracelet which form no part of the claimed design.
